UNITED STATES PATENT OFFICE

146,020

DESIGN FOR A BOX OR THE LIKE

Lyle E. Elliott, Battle Creek, Mich.

Application August 11, 1945, Serial No. 121,394

Term of patent 7 years

(Cl. D58—12.6)

To all whom it may concern:

Be it known that I, Lyle E. Elliott, a citizen of the United States, residing at Battle Creek, in the county of Calhoun and State of Michigan, have invented a new, original, and ornamental Design for a Box or the like, of which the following is a specification, reference being had to the accompanying drawings, which form part thereof.

I claim:

The ornamental design for a box or the like, substantially as shown.

LYLE E. ELLIOTT.
